US0D1019279S

(12) **United States Design Patent** (10) **Patent No.:** **US D1,019,279 S**
(45) **Date of Patent:** ** *Mar. 26, 2024

(54) **CUP**

(71) Applicant: **Bockatech Ltd.**, Huntingdon (GB)

(72) Inventors: **Lewis Wood**, Huntingdon (GB);
Martin Blacher, Huntingdon (GB)

(73) Assignee: **Bockatech Ltd.**, Huntingdon (GB)

(*) Notice: This patent is subject to a terminal disclaimer.

(**) Term: **15 Years**

(21) Appl. No.: **29/832,566**

(22) Filed: **Mar. 29, 2022**

(30) **Foreign Application Priority Data**

Sep. 30, 2021 (GB) 6167310

(51) **LOC (14) Cl.** **07-01**

(57) **CLAIM**

The ornamental design for a cup, as shown and described.

DESCRIPTION

FIG. 1 is a front perspective from below view of a cup according to our new design;

FIG. 2 is a front perspective from above view thereof;
FIG. 3 is a bottom plan view thereof;
FIG. 4 is a front elevational view thereof;
FIG. 5 is a rear elevational view thereof;
FIG. 6 is a right-side elevational view thereof, the left-side
elevational view (not shown) being the same; and,
FIG. 7 is a top plan view thereof.
The broken lines depict portions of the cup that form no part
of the claim.
